UNITED STATES PATENT OFFICE.

AUGUST F. ERN, OF SCARSDALE, NEW YORK, ASSIGNOR TO K. C. SEELBACH COMPANY,
OF NEW YORK, N. Y., A CORPORATION OF NEW YORK.

DESIGN FOR A PAIR OF SCISSORS.

Application filed June 15, 1927. Serial No. 22,435. Term of patent 7 years.

To all whom it may concern:

Be it known that I, AUGUST F. ERN, a citizen of the United States, and resident of Scarsdale, in the county of Westchester and State of New York, have invented a new, original, and ornamental Design for a Pair of Scissors, of which the following is a specification, reference being had to the accompanying drawing, forming part thereof.

The figure is a plan view of a pair of scissors, showing my new design.

The dominant features reside in the contour of the handles and the checkered ornamentation applied thereto.

I claim:

The ornamental design for a pair of scissors, as shown and described.

Signed at New York city in the county of New York, and State of New York, this 11th day of June A. D. 1927.

A. F. ERN.
